(57) **CLAIM**

The ornamental design for a display screen portion with graphical user interface, as shown and described.

DESCRIPTION

The present application is also related to U.S. Design patent application Ser. No. 29/623,844, filed Oct. 27, 2017; U.S. Design patent application Ser. No. 29/623,815, filed Oct. 27, 2017; U.S. Design patent application Ser. No. 29/679,663, filed Feb. 8, 2019; U.S. Design patent application Ser. No. 29/623,820, filed Oct. 27, 2017, now U.S. Design Pat. No. D847,858; U.S. Design patent application Ser. No. 29/680, 898, filed Feb. 21, 2019; U.S. Design patent application Ser. No. 29/623,826, filed Oct. 27, 2017; and U.S. Design patent application Ser. No. 29/623,833, filed Oct. 27, 2017, the entire disclosures of which are incorporated herein by reference.

FIG. 1 is a front view of a display screen portion with graphical user interface according to our design.

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof; and,

FIG. 8 is an eighth image thereof.

The dot-dash broken line showing of the display screen portion and all other broken line showing portions of the graphical user interface are included for the purpose of illustrating portions of the article that form no part of the claimed design. In the figures, the perimeters of the portion of the underlying display screen and the graphical interface are understood to be flush.

The appearance of the image sequentially transitions between FIGS. 1-8. The process or period in which one image transitions to another image forms no part of the claimed design.
